UNITED STATES PATENT OFFICE.

JOHN M. SCHILLING, OF LIMA, OHIO.

DESIGN FOR A CABINET FOR BOTTLE COOLERS.

Application filed December 19, 1927. Serial No. 24,551. Term of patent 14 years.

To all whom it may concern:

Be it known that I, JOHN M. SCHILLING, a citizen of the United States, residing at Lima, in the county of Allen and State of Ohio, have invented a new, original, and ornamental Design for Cabinets for Bottle Coolers, of which the following is a specification, reference being had to the accompanying drawing forming a part thereof.

The drawing shows a perspective view of the article, showing my new design.

I claim:

The ornamental design for a cabinet for bottle coolers as shown.

In witness whereof, I hereunto subscribe my name this 10th day of December, A. D. 1927.

JOHN M. SCHILLING.
